CABLE OPERATED CLOSING MEANS FOR
BAGS AND SUITCASES

Victor Fiorucci, Nice, France

Application August 17, 1949, Serial No. 110,802
In France November 9, 1948

9 Claims. (Cl. 150—11)

1

Suit-cases having a yielding cover are generally provided with a so-called lightening or zip fastener. It often occurs that such closing means are defective in operation due to numerous reasons and much time is lost for restoring them into their proper operative state. On the other hand, zipper closing means does not provide perfect fluidtightness for the suit-cases and their contents may be submitted to damage by reason of the possible seeping of water or the like objectionable fluid material inside it.

According to my invention, I provide suit-cases of any description with a very simple closing system that removes these drawbacks, that is practically proof against misadjustment and provides for perfect fluidtightness of the suit-case.

This closing system includes chiefly a normally slack cable lying over all or part of the periphery of the edge opening of the cover of the suit-case and provided with fastening means, operable through a small outer lever controlling the tensioning and slackening of the cable.

In an embodiment of the invention the case may be closed tight by a tensioning device incorporating a cam and a pawl and ratchet to provide a gradual tensioning of a cable and prevent untimely slackening of the cable. It also provides means that prevent passing a hand between the edges forming the opening of the bag when the cable is tensioned.

My invention is applicable to any suit-cases even of a rigid type provided they incorporate a yielding sheath inside which the cable may slide, the remainder of the cover edge and the upper part thereof being rigid if required.

Embodiment of my invention is illustrated in accompanying drawing, wherein:

Fig. 1 is a perspective view of a suit-case with a yielding cover provided with my improved closing means.

Fig. 2 is a fragmentary sectional view of the suit case.

Fig. 3 is a sectional view of the cable actuating means.

Fig. 4 is a sectional view through line X—X of Fig. 3.

Figs. 5 and 6 are detail views of the safety means that prevents engaging one's hand between the cover and the body of the suit-case.

Turning to the embodiment illustrated in Figs. 1 to 4, the closing system includes a cable 1 of which one end is secured to a stationary point 2 and the other to a point 3 in the peripheral groove of a cam 4. This cable is positioned in the extreme edge portion of the cover, which edge

2

portion is then folded over and secured through sewing or any other suitable means to form a flexible sheath for the cable.

The lateral corners of the walls of the suitcase cover and body are rounded to allow the sheathed cable to hug the underlying surfaces.

The cam 4 is mounted to turn with its shaft 5 in a casing 11, which casing is secured outside the suitcase cover; said cam is provided on its curved periphery with a notch or notches 6 engageable by a pawl 8 when in register. An outside lever 7 is keyed to shaft 5 to turn the cam 4 within the casing 11 when the pawl 8 is disengaged from the notch 6 by a removable key 12 against the resistance of a pawl spring 10. The spring 10 normally moves the pawl 8 towards the curved periphery of said cam. When the pawl 8 is disengaged from the notch 6, the cable is provided with sufficient slack, and the suitcase may be opened. By moving the lever 7 from the position shown in dotted lines to that shown in dash and dot lines in Figure 3, the cable is tensioned to take up the slack, and the cover of the suitcase is locked to the body of the same.

Throughout or a part of the periphery of the wall of the suit-case body is provided with a bead 13 constituted by a small rod of semi-circular cross-section or by a rib integral with the suitcase wall if the latter is of metal. The edge of the cover carrying the cable sheath registers with said projection or bead 13 so that the cable when tensioned, said cable is then locked against the lower edge of said projection. It is also possible to provide two cables located to either side of the projection or again two projections and two cables which allow a tighter casing to be obtained.

The operation of the closing system is as follows:

The extreme edge of the cover is fitted over the bead 13. The lever 7 is then moved so as to turn the cam 4 and to tension the cable 1 held inside the groove of said cam; the cable pressure exerted on the edge of the cover and the wall of the suit-case body under cover and on the lower portion of the bead 13; thus providing a perfect closing and absolute fluid tightness of the suit-case.

The lever 7 is locked in closed position of the suitcase through the action of the spring 10 on the pawl 8 which engages the notch 6 in the cam 4. To move the lever 7 back and thereby to slacken the cable for opening the cover, it is sufficient to move the key 12 to disengage the pawl 8 from the cam whereby it is possible to return the lever 7 into its starting cable releasing position that is, providing cable slack.

The arrangement illustrated in Figs. 5 and 6 is to prevent any one inserting a hand inside the suit-case by moving the edge of the cover away from the body thereof when the cable is tensioned. Said arrangement carried on the body of the suit-case includes one or more forks 41 located in the immediate vicinity and just underneath the bead 13 on the suit-case body; one or more rivets 42 are rigidly secured just above the sheath containing the cable 1 whereby when drawing in the cable for closing the suit-case, the rivets 42 engage the interval between the arms of the fork 41 which positively prevents any moving of the edge of the cover with reference to the wall of the suit-case body.

Furthermore, instead of providing a bead 13 as hereinbefore described for engagement with the cable, it is possible to provide a groove inside which said cable fits tightly when it is stretched.

Obviously the closing means described may be submitted to various modifications within the scope of accompanying claims while the parts forming it may be designed in any shape and size and of any material as desired or convenient.

What I claim is:

1. In suit-cases and the like containers provided with a body and a cover overlapping same, a closing arrangement including a sheath provided along the edge of the cover of the container, a cable lying inside said sheath and hand-operable means acting on the cable for tensioning same and clamping it into engagement with the underlying portion of the container body; at least one forked member located on the body of the container in register with the path followed by the cable and at least one projection carried by the cable sheath engageable with said fork upon tensioning of the cable.

2. In a suitcase, a rigid bead on the face at one edge of the case opening and substantially parallel to the edge, a sheath of flexible material at the other edge of the opening, a normally slack cable in the sheath having its ends anchored at the ends of the sheath, said sheathed cable lying below the rigid member when the opening is closed, cable tensioning means secured to the sheath edge and engaging the cable, and separable interlocking means positioned at the edges of the opening and locking when the cable is tensioned to bring the same against the bead.

3. A suitcase having a rigid bead at one edge of the opening and parallel thereto, a sheath of flexible material bordering the other edge of the opening, a normally slack cable in the sheath having the ends thereof anchored to the ends of the sheath, said sheathed cable lying below the rigid member when the opening is closed, cable tensioning means secured to the sheath edge and engaging the cable, and separable interlocking means positioned at the edges of the opening on the outer surface of the rigid member and inner surface of the sheathed edge and adapted to be locked when the sheathed cable is tensioned to bring the same against the bead when the opening is closed.

4. A suitcase having an outer rigid bead at one edge of the opening thereof and in conformity with the shape of the case at the opening, a sheath of flexible material at the other edge of the opening, a normally slack cable in the sheath having one end anchored to an end of the sheath, said sheathed cable adapted to lie below the lower edge of the bead when the case is closed, cable tensioning means secured to the other end of the sheath edge and engaging the other end of the

cable, and separable interlocking means having parts secured near the edge of the sheathed cable and cooperating parts secured on the edge where the bead is provided, said parts adapted to interlock when the cable is tensioned to bring the same against the lower edge of the bead when the case is closed.

5. A suitcase comprising a body section and a cover section hinged to the body section, the corners of the lateral walls of both sections being rounded, the said lateral walls of the cover adapted to nest the proximate parts of said lateral walls of the body section when the cover is closed on the body, rigid beaded sections on the rounded corners of the body walls below the exposed edges of said walls and substantially parallel to said edges and in a substantially common plane, a flexible sheath bordering the exposed edges of the walls of the cover to locate below the said beads when the cover is closed, a normally slack cable in said sheath having its ends anchored to the cover at the sheath ends, and a cable tensioning device secured to the cover at the sheath to engage the cable to tension the same in the sheath about the nested walls of the body and against the said beads when the case is closed.

6. A suitcase having a body section and a cover section, said body and cover sections having the corners between their lateral walls rounded, said cover walls nesting the upper portion of said body walls when the cover is on the body, the edges of the body and cover walls defining the case opening, said rounded corners of the body section having means on the face thereof disposed below said edges of said body section and parallel thereto, a sheath of flexible material bordering the exposed edges of the cover and adapted to locate at the means when the cover is closed, a normally slack cable in the sheath having its ends anchored to the cover at the sheath ends, and a cable tensioning device secured to the cover and engaging the cable to draw the sheathed cable against the nested walls of the body section to engage the means when the cable is tensioned while the case is closed.

7. A suitcase having rounded wall corners rising from the bottom and extending from the top, the rounded walls of the top nesting the proximate upper portions of the walls rising from the bottom when the case is closed, the exposed edges of said top and bottom walls defining the opening of the case, a sheath of flexible material bordering the exposed edges of the top, a normally slack cable in the sheath having its ends anchored to the cover at the ends of the sheath, cable tensioning means secured to the top and engaging the sheathed cable, and alining spaced apart co-planar beads of rigid material on the walls rising from the bottom; said beads adapted to lie above the sheathed cable when the case is closed, said sheathed cable adapted to engage the lower edge of said beads when the sheathed cable is tensioned against the portion of the walls nested under the walls of the cover.

8. A suitcase having a body section and a cover section, said body and cover sections having the corners between their lateral walls rounded, said cover walls nesting the upper portion of said body walls when the cover is on the body, the edges of the body and cover walls defining the case opening, said body section having means on the outer face thereof disposed below the edge of said walls and parallel thereto, a sheath of flexible material bordering the exposed edges of the cover and adapted to locate at the means when the cover

is closed, a normally slack cable in the sheath having its ends anchored to the cover at the sheath ends, and a cable tensioning device secured to the cover at the sheath and engaging the cable to draw the sheathed cable against the nested walls of the body section and into engagement with the means when the cable is tensioned while the case is closed.

9. A suitcase, comprising a body section having rigid walls, a cover for said body section, a normally slack cable carried by the unattached edges of the cover and sheathing said cable thereat to permit a relative movement between the cable and sheath, cable actuating means secured to the cover and engaging the cable, said body section having means on the outer face of the walls below the edges engageable by the cover to underlie said sheathed cable, said latter means being

adapted to be engaged by the sheathed cable when the cable is tensioned by the cable actuating means and whereby the cover is locked to the body.
